UNITED STATES PATENT OFFICE.

JOHN F. GALVIN, OF NEW YORK, N. Y.

DESIGN FOR A FASTENER.

45,909.

Specification for Design.

Patented June 9, 1914.

Application filed February 7, 1912. Serial No. 676,152. Term of patent 7 years.

To all whom it may concern:

Be it known that I, JOHN F. GALVIN, a citizen of the United States, residing in the city, county, and State of New York, have invented a new, original, and ornamental Design for Fasteners, of which the following is a specification, reference being had to the accompanying drawing, forming part thereof.

Figure 1 is a top plan view showing the design when the button is in one position; Fig. 2 is a side view of the design; Fig. 3 is an end view.

The design consists of a base A, of elliptical shape, and a flange a of elliptical shape. The top of the base has a longitudinal de-

pression, a^1 , and a transverse depression, a^2 . The button B is of less thickness than the base, and has an under side, b, and a rounded outer edge b^1 .

I claim:

The ornamental design for a fastener as shown and described.

In witness whereof, I have hereunto set my hand at the city, county and State of New York, this second day of February, 1912.

JOHN F. GALVIN.

In presence of—

JOHN J. RANAGAN,
ISABEL R. RICHARDS.
